UNITED STATES PATENT OFFICE.

GEORGE EMMET QUIGLEY, OF YOUNGSTOWN, OHIO.

STEAM-ENGINE.

1,163,452.

Specification of Letters Patent.

Patented Dec. 7, 1915.

Application filed August 12, 1914. Serial No. 856,373.

To all whom it may concern:

Be it known that I, GEORGE E. QUIGLEY, a citizen of the United States, and a resident of Youngstown, in the county of Mahoning and State of Ohio, have invented certain new and useful Improvements in Steam-Engines, of which the following is a specification.

My invention relates to steam engines, 10 and it consists in the combinations, constructions, and arrangements herein described and claimed.

An object of my invention is to provide a steam engine having a cylinder body which 15 does not have to be cored, owing to the fact that passage-ways or ports are provided in separate port carriers.

A further object of my invention is to 20 provide an engine in which the coring of the cylinder saddle is obviated.

A further object of my invention is to 25 provide an engine having a novel form of bushing in which the slotting of the bushing is eliminated, the said bushing being held in position by novel holding devices.

A further object of my invention is to 30 provide an engine having a cylinder and a valve casing, said cylinder being provided with port carriers for establishing communication between the cylinder and the valve casing, the said port carriers also serving as means for supporting the valve casing.

A further object of my invention is to 35 provide an engine having means for carrying off the exhaust steam, which is not dependent upon a cored saddle, but which may be used with any suitable form of cylinder support.

Other objects and advantages will appear 40 in the following specification, and the novel features of the invention will be particularly pointed out in the appended claims.

My invention is fully described in the following specification, of which the accompanying drawings form a part, in which the same reference characters are used to designate the same parts in each of the views, and in which:

Figure 1 is a central, longitudinal, vertical, section taken through one unit of a locomotive engine constructed in accordance with my present invention; Fig. 2 is a section taken on the line 2—2 of Fig. 1; Fig. 3 is a section taken on the line 3—3 of Fig. 1; Fig. 4 is a plan view of two connected units; Fig. 5 is a perspective view of one of the

cylinder heads which I employ; Fig. 6 is a section taken on the line 6—6 of Fig. 4.

In the drawings forming a part of this application I have shown a present preferred form of embodiment of my invention as applied to a locomotive engine, comprising a cylinder body *a*, having exactly similar heads *b*, two exactly similar port casings or carriers *c*, interposed between the cylinder body and corresponding heads, two exactly similar valve chamber casings *d* joined together between the port carriers, two exactly similar valve chamber extensions *e* on the outer faces of corresponding port carriers, two exactly similar bushings *f* within the valve chamber, and two exactly similar exhaust T's *h* connected with corresponding valve chamber extensions *e* of each of the units of the engine, as shown in Fig. 4, and a T *i* exactly like the T's *h* and joining the same.

The valve chamber casings *d* are joined together by means of bolts *d*² and to the corresponding port carriers *c* by means of bolts *d*³, and each of said casings having an inlet connection *d*⁴, one for the steam and the other for the relief valve, and said port carriers are connected with the cylinder *a* by means of bolts *a*², said cylinder being shown with a bushing or lining *a*³.

The cylinder heads *b* are connected with the corresponding port carriers *c* by means of bolts *b*², each of said heads having an inwardly directed member *b*³, extending into the opening *c*² of the corresponding port carrier, internal webs *b*⁴, an external boss *b*⁵ and screw-threaded openings *b*⁶ therethrough, each of which is adapted to receive a gland *b*⁷ or *b*⁸, the former of which is bored for the piston rod *k* of the piston *k*², and the latter being blind for the closed end of the cylinder, and it will be seen that said heads *b* are readily interchangeable.

The valve chamber extensions *e* are connected with corresponding port carriers by means of bolts *e*² and have, each, a head *e*³, exactly alike, connected therewith by means of bolts *e*⁴, each of said heads having a boss *e*⁵ thereon provided with a screw-threaded opening therethrough adapted to receive either of two glands *e*⁷ or *e*⁸, the former of which is bored for the stem *l* of a double valve *l*², and the latter of which is blind at the closed end of the valve chamber, and the exhaust T's *h* are connected with corresponding valve chamber extensions *e* by

means of bolts h^2 , the T's h being connected with the T i by means of bolts i^2 , and it will be seen that the extensions e are each provided with an opening e^9 in the positions of 5 corresponding exhaust T's h .

The port carriers c have, each, the opening c^2 referred to, as well as a registering opening c^3 communicating with the interior of the cylinder a , and two openings c^4 and c^5 10 in register and communicating with the corresponding valve chamber casings d and extensions e , the bushings f resting within the openings c^4 and c^5 of the corresponding port carriers, and it will be noted that the said 15 bushings are each provided with a plurality of ports f^2 communicating with the interior of the corresponding port carriers whereby "dead" steam may be exhausted from the cylinder to the T i , at each end of said 20 cylinder, alternately, this being controlled by the members b^3 of the valve b^2 , said members also controlling the admission of steam to the cylinder, on opposite sides of the piston k^2 from the inlet d^4 , through corresponding 25 ing port carriers.

In assembling the engine, the body portion a of the cylinder is provided with a bushing a^3 as stated, which is simply a cylindrical member without any cut-away portion or 30 opening. The bushing is held in place by means of the webs b^4 on the cylinder heads b . These webs, as will be seen from the drawings, project through the opening c^3 in the port carrier c . This means of holding 35 the bushing in place, does away with any necessity of the use of dowel pins or other similar devices, and eliminates the necessity of boring dowel pin holes through the bushing or the body of the cylinder. The provision 40 of the ports or passages in the port carrier c eliminates the necessity of having intricate cored passage-ways in the body a of the cylinders. The latter is, like the bushing, a single member which does not require 45 machining to provide ports or means for holding the bushing. The port carrier c serves a double purpose, for it not only provides a passage-way for the steam, but it also serves as a supporting means for the 50 valve casing.

The provision of the exhaust T's obviates the necessity of providing a cored saddle for the cylinders. The cylinders, therefore, may be secured to any convenient portion of 55 the engine or locomotive.

The operation is in all respects similar to that of the conventional engines, but it will be seen that, in the event of injury to any part thereof, such part may be quickly and 60 easily replaced, for the most delicate and most inaccessible port slots of the present type of engines is rendered quickly and easily accessible and replaceable, only the particular port carrier being removed and 65 another substituted therefor, and it will also

be noted that, in the event of an irreparable injury, only the port carrier is scrapped, and no tying up of the locomotive is necessary beyond the few hours required to substitute a new port carrier. This is equally true of 70 the other parts, such as the cylinder heads, the glands therein, the valve chamber casings, the extensions thereof, the bushings therein, the heads of said chamber, and the glands thereof, it not being necessary to take 75 down the entire engine to replace any of these parts, and only a small portion of the engine need be scrapped if found irreparable, substitute parts being carried in stock in all shops along the right of way, and, if 80 the cylinder a should be badly damaged, only a relatively small casting need be scrapped. Further, because of the number of joints, the liability of injury to the engine is minimized because of the comparative 85 flexibility at such points, and the original cost of production of the engine is greatly reduced because of the fact that the cylinder and valve chamber are absolutely distinct from each other, and comprise, each, relatively simple parts requiring little machining as compared with the cumbersome cylinder castings as now provided, with the intricate machining thereof. 90

While I have shown an adaptation of my 95 invention to locomotive engines, it will be obvious that I may adapt the same to marine and stationary engines as well, and I may make structural changes within the scope of the appended claims over the details illustrated in order to adapt the same to such other uses, but I have shown the same in connection with a locomotive because of the exposure of such engines to sudden atmospheric changes in temperature over the steam 100 temperatures. 105

Having fully described my invention, what I do claim as new, and desire to secure by Letters Patent, is:—

1. The combination with a cylinder body, 110 of port carriers secured at each end of said cylinder body, and a head secured to each of said port carriers.

2. The combination with a cylinder body, 115 of a detachable port carrier secured at each end of said cylinder body, a detachable head secured to each of said port carriers, a bushing disposed loosely within said cylinder body, and means for holding said bushing in place. 120

3. The combination with a cylinder body, 125 of a detachable port carrier secured at each end of said cylinder body, a detachable head secured to each of said port carriers, a bushing disposed loosely within said cylinder body, and means carried by said heads for holding said bushing in place.

4. The combination with a cylinder body, 130 of a detachable port carrier secured at each end of said cylinder body, a detachable head

- secured to each of said port carriers, a bushing disposed loosely within said cylinder body, and webs carried by said heads for holding said bushing in place. 55
5. In an engine, a cylinder body, a port carrier secured to said cylinder body at each end thereof, each of said port carriers having a central opening, and heads for closing said central openings. 60
10. In an engine, a cylinder body portion, a port carrier secured to said cylinder body portion at each end thereof, each of said port carriers having an opening registering with the interior of the cylinder, a head secured to each of said port carriers and arranged to cover the opening, and ports carried by said port carriers and communicating at one end with said central opening. 65
15. In an engine, a cylinder body portion, a port carrier secured to said cylinder body portion at each end thereof, each of said port carriers having an opening registering with the interior of the cylinder, a head secured to each of said port carriers and arranged to cover the opening, ports carried by said port carriers and communicating at one end with said central opening, a bushing disposed within said cylinder body, and flanges carried by said heads and arranged 70
20. to project through the central openings of said port carriers and into engagement with the ends of said bushing for holding the latter in place. 75
25. The combination with a cylinder body portion, of port carriers secured to the ends of said body portion, each of said port carriers being provided with a pair of openings extending through said port carriers, one of said openings registering with the interior 80
30. diameter of the cylinder body, heads for covering each of said last named openings, and a valve casing supported conjointly by said port carriers. 85
35. The combination with a cylinder body portion, of port carriers secured to the ends of said body portion, each of said port carriers being provided with a pair of openings extending through said port carriers, one of said openings registering with the interior 90
40. diameter of the cylinder body, heads for covering each of said last named openings, and a valve casing supported conjointly by said port carriers. 95
45. The combination with a cylinder body portion, of port carriers secured to the ends of said body portion, each of said port carriers being provided with a pair of openings extending through said port carriers, one of said openings registering with the interior 100
50. diameter of the cylinder body, heads for covering each of said last named openings, and a valve casing supported conjointly by said port carriers. 105
5. In an engine, a cylindrical body portion, a pair of port carriers secured to the ends of said cylindrical body portion, each of said port carriers being provided with a large cylindrical opening arranged to register with the interior wall of said cylindrical body portion and a smaller cylindrical opening, the axis of these cylindrical openings being parallel with the axis of the cylinder, ports in each port carrier connecting its smaller opening with its larger opening, and a common valve casing having its interior wall registering with each of the smaller cylindrical openings. 110
10. In an engine, a cylindrical body portion, a pair of port carriers secured to the ends of said cylindrical body portion, each of said port carriers being provided with a large cylindrical opening arranged to register with the interior wall of said cylindrical body portion and a smaller cylindrical opening, the axis of these cylindrical openings being parallel with the axis of the cylinder, ports in each port carrier connecting its smaller opening with its larger opening, and a common valve casing having its interior wall registering with each of the smaller cylindrical openings. 115
15. In an engine, a cylindrical body portion, a pair of port carriers secured to the ends of said cylindrical body portion, each of said port carriers being provided with a large cylindrical opening arranged to register with the interior wall of said cylindrical body portion and a smaller cylindrical opening, the axis of these cylindrical openings being parallel with the axis of the cylinder, ports in each port carrier connecting its smaller opening with its larger opening, and a common valve casing having its interior wall registering with each of the smaller cylindrical openings. 120
20. The combination with a cylinder body portion, of port carriers secured to the ends of said body portion, each of said port carriers being provided with a pair of openings extending through said port carriers, one of said openings registering with the interior 125
25. diameter of the cylinder body, heads for covering each of said last named openings, and a valve casing supported conjointly by said port carriers. 130
30. The combination with a cylinder body portion, of port carriers secured to the ends of said body portion, each of said port carriers being provided with a pair of openings extending through said port carriers, one of said openings registering with the interior 135
35. diameter of the cylinder body, heads for covering each of said last named openings, and a valve casing supported conjointly by said port carriers. 140
40. The combination with a cylinder body portion, of port carriers secured to the ends of said body portion, each of said port carriers being provided with a pair of openings extending through said port carriers, one of said openings registering with the interior 145
45. diameter of the cylinder body, heads for covering each of said last named openings, and a valve casing supported conjointly by said port carriers. 150
50. The combination with a cylinder body portion, of port carriers secured to the ends of said body portion, each of said port carriers being provided with a pair of openings extending through said port carriers, one of said openings registering with the interior 155
55. diameter of the cylinder body, heads for covering each of said last named openings, and a valve casing supported conjointly by said port carriers. 160
60. The combination with a cylinder body portion, of port carriers secured to the ends of said body portion, each of said port carriers being provided with a pair of openings extending through said port carriers, one of said openings registering with the interior 165
65. diameter of the cylinder body, heads for covering each of said last named openings, and a valve casing supported conjointly by said port carriers. 170
70. The combination with a cylinder body portion, of port carriers secured to the ends of said body portion, each of said port carriers being provided with a pair of openings extending through said port carriers, one of said openings registering with the interior 175
75. diameter of the cylinder body, heads for covering each of said last named openings, and a valve casing supported conjointly by said port carriers. 180
80. The combination with a cylinder body portion, of port carriers secured to the ends of said body portion, each of said port carriers being provided with a pair of openings extending through said port carriers, one of said openings registering with the interior 185
85. diameter of the cylinder body, heads for covering each of said last named openings, and a valve casing supported conjointly by said port carriers. 190
90. The combination with a cylinder body portion, of port carriers secured to the ends of said body portion, each of said port carriers being provided with a pair of openings extending through said port carriers, one of said openings registering with the interior 195
95. diameter of the cylinder body, heads for covering each of said last named openings, and a valve casing supported conjointly by said port carriers. 200

In testimony whereof I have signed my name to this specification in the presence of the subscribing witnesses.

GEORGE EMMET QUIGLEY.
